UNITED STATES PATENT OFFICE.

CHRISTIAN W. WINTHER, CLARENCE W. WINTHER, AND LENNA V. WINTHER, OF FRESNO, CALIFORNIA.

CYLINDER-LAPPING MACHINE.

Application filed April 17, 1922. Serial No. 553,940.

To all whom it may concern:

Be it known that we, CHRISTIAN W. WINTHER, CLARENCE W. WINTHER, and LENNA V. WINTHER, all citizens of the United States, and residents of Fresno, in the county of Fresno, State of California, have invented certain new and useful Improvements in Cylinder-Lapping Machines, of which the following is a specification.

Heretofore in the use of an explosion engine, when the cylinders become worn it has been customary to reboore or reground the cylinders which necessitates fitting new pistons and this necessitates the dismantling of the engine in order that the block might be removed to the machine to be used in regrounding or reboring the cylinders, entailing a considerable expenditure of time and trouble. It is the object of our invention to provide means whereby the cylinders may be reground or lapped and new pistons fitted therein without removing the same from its place of use and without removing any part of the engine other than the cylinder head.

A further object is to provide a device for the above purpose which may be easily and quickly transported from place to place and which may be easily and quickly attached to the cylinder block by means of the bolts used to hold the cylinder head positioned, and which may be easily and quickly adjusted to its position for use.

Other objects and advantages will appear hereinafter, and while we have shown and will describe the preferred form of our invention, it will be understood that we do not limit ourselves to such preferred form but that various changes and adaptations may be made therein without departing from the spirit of our invention.

In the drawings accompanying and forming a part hereof:

Fig. 1 is a side elevation of a portion of a cylinder block with our device positioned thereon in position for use.

Fig. 2 is a side elevation of our device on an enlarged scale.

Fig. 3 is a front elevation of Fig. 2.

Fig. 4 is an enlarged sectional detail of the elevating mechanism.

Fig. 5 is an enlarged detail view, partly broken away, of the piston operating spindle.

Fig. 6 is an enlarged detail of the piston operating mechanism.

Fig. 7 is a fragmentary top elevation of our driving disc.

Referring to the drawings, our device comprises a base 10, provided with a slot 11 through which the bolt 12 passes into one of the cylinder head bolt holes to retain the device in its position for use, the slot permitting the adjustment necessary in order to centralize the device over the cylinder to be lapped. At one end of member 11 are provided vertical bearings 13 and 14 in which are rigidly secured the lower ends of vertically extending guide rods 15 and 16. Slidably mounted on rods 15 and 16, to slide vertically, are hollow, tubular slide members 17 and 18, the upper ends of which terminate in and are connected by an integral bracket 19, from which bracket extends rearwardly, equally spaced from rods 15 and 16, a horizontal bearing 20, the free end of which terminates in a gear case 21. Formed on slide members 17 and 18, a short distance below bracket 19, are bosses 22 and 23 provided with an outwardly extending shelf 24 upon which is mounted the motor 25. Revolubly mounted in bearing 20 is a shaft 26 upon one end of which is rigidly mounted a disc 27 and on the other end is rigidly mounted a worm wheel 28 which meshes with a worm 29 mounted on the end of shaft 30 of motor 25, whereby said shaft 26 is rotated. Formed in disc 27 is a radially extending slot 31 surrounded by a pad 32, and slidably mounted in slot 31 is a pintle bolt 33. Pintle bolt 33 is square where it passes through slot 31 to prevent retation of said bolt in said slot, and is provided with a squared head 34. Detachably mounted on bolt 33 is a bevel gear 35, the back of which abuts against the pad 32 of disk 27, and is provided with a sleeve 36 extending from its front face, which sleeve is revolubly mounted within a bearing 37 upon the upper end of bracket 38. A washer 39 and a nut 40 on the end of pintle 33 provide means for locking gear 35 against rotation upon said pintle 33. The other end of bracket 38 terminates in a vertical bearing 41 in which is adjustably mounted a bushing 42, adjustable vertically. Revolubly mounted in bushing 42 is the operating spindle 43, upon

the upper end of which is rigidly mounted a bevel gear 42^a which normally meshes with gear 35. The lower end of spindle 43 terminates in a fork 44, within the fork end of 5 which is pivotally mounted a block 45. Slidably mounted upon members 17 and 18 are bearings 46 and 47 connected together by a cross member 48, and extending forwardly from member 48, centrally thereof, 10 is a bearing 49. Revolvably mounted in bearing 49 is a sleeve 50, on the upper end of which is a flange 51 which rests upon the upper end of bearing 49. Extending upwardly from flange 51 are oppositely disposed ears 52 and 53 in which ears is pivotally mounted block 45 at right angles to fork 44, this construction forming what is known as a universal joint. Detachably mounted within sleeve 50 is the piston 15 spindle 54, the lower end of which terminates in a flexible or universal connection 55, adapted to be mounted upon the piston pin of the piston. Revolvably mounted in the upper end of boss 23 is a gear 56 which meshes with teeth 57 in guide rod 15, and a handle 58 provides means for rotating said gear 56, whereby the slide members 17 and 18 and their component parts are elevated or lowered as desired. A locking screw 59 20 projecting through said boss 23 provides means for locking the device in its adjusted position by means of a handle 60.

In the operation of our device the device 25 will first be positioned upon the cylinder block with the piston spindle as nearly centrally of the cylinder to be operated upon as possible. Bolt 12 will then be tightened to hold the device against accidental movement. The screw 59 will then be loosened and handle 58 operated to rotate gear 56 to the desired height so that the piston may be inserted in the cylinder. With the spindle 40 54 positioned in sleeve 50 the said screw 62 will then be tightened to hold spindle 54 in its adjusted position. The spindle 33 will then be adjusted within slot 31 to provide the desired stroke of the spindle 43, this stroke being conditioned upon the stroke or 45 length of the cylinder or the portion of the cylinder it is desired to operate upon. Gear 56 will then be operated to lower the device to the desired position for operation and lock nut 59 will be used to lock the same in this position. Emery or other grinding compound will be used upon the walls of the cylinder and the motor will then be operated thereby rotating disc 27, the rotation of disc 27 causing a vertical movement of spindle 54 and at the same time, through bevel gears 55 59 and 42^a, imparting a rotary movement to spindle 54, thus providing a combined reciprocating and rotary movement to the piston within the cylinder. Should it be desired to use a vertical movement only, said 60 screw 63 in bearing 41 will be loosened until

the end is withdrawn from recess 64 in bushing 42. Bushing 42 will then be lowered until recess 65 registers with the end of screw 63. Screw 63 will then be tightened and the device is ready for use, it being understood that as bushing 42 is lowered gear 42^a will also be lowered and withdrawn from engagement with gear 35. Should it be desired to use the rotative movement only, pintle 33 will be lowered in slot 31 until gear 35 is 65 centrally of shaft 26, the result of which will be obvious.

Having described our invention what we claim is:

1. A cylinder lapping machine comprising 80 a frame adapted to be detachably mounted upon the upper end of a cylinder block; vertically extending guide members carried by said frame; means mounted on said guide members to slide vertically and adapted to carry a piston; means carried by said frame to impart a vertical reciprocating movement to said slide members, and means operated by said last means to impart a continuous horizontal rotating movement to said piston always in the same direction during its reciprocation; and means to vary the length of said reciprocating movement. 85

2. A cylinder lapping machine comprising 90 a frame; a pair of guide members extending upwardly from said frame; a pair of slide members mounted upon said guide members; a bearing carried by the upper ends of said slide members at right angles thereto; a disc revolvably mounted in said 100 bearing; a bevel gear adjustably mounted on the face of said disc, adjustable radially; a bearing carried by said gear in which the same is revolvably mounted; a bearing connected to said last bearing at right angles 105 thereto; a spindle revolvably mounted in said last bearing; a gear on the upper end of said spindle in operative engagement with said first mentioned gear; a bearing slidably mounted upon said slide members 110 to slide vertically; a sleeve revolvably mounted in said bearing; a universal connection between said sleeve and said spindle; a spindle detachably mounted at its upper end in said sleeve and adapted to be flexibly connected to a piston on its lower end; means to raise or lower said slide members relative to the guide members; means to lock said slide members in their desired position; and means to operate said disc. 115

3. A cylinder lapping machine comprising 120 a frame adapted to be detachably mounted upon the upper end of a cylinder block; vertically extending guide members carried by said frame; means mounted on said guide members to slide vertically and adapted to carry a piston; means carried by said frame to impart a reciprocating movement to said slide members; means operated by said last means to impart a continuous rotating move- 125

ment always in the same direction to said piston during its reciprocation; and means to regulate the extent of said reciprocating movement.

4. In a lapping machine a frame adapted to be adjustably mounted upon the upper end of a cylinder; a vertically slidable member carried by said frame; a work engaging member carried by said slidable member; means mounted on said frame for rotating said work holding member continuously in the same direction; and means operated by said last means for imparting a vertical reciprocating movement to said work holding member synchronously with said rotating movement, said reciprocating movement and rotating movement being completed simultaneously.

5. A cylinder lapping machine comprising a frame adapted to be adjustably mounted upon the upper end of a cylinder block; a vertically slidable member carried by said frame; a work holding member mounted on the lower end of said slidable member; a universal joint between said slidable member and work holding member; means carried by said frame for imparting a continuous horizontal rotating movement to said work holding member; means operated by said last means for imparting a vertical reciprocating movement to said work holding member synchronously with said work holding member; means to vary the length of said reciprocating movement; and means to adjust said work holding member relative to the work.

6. A lapping machine comprising a frame adapted to be adjustably mounted upon the upper end of a cylinder block; vertically extending guide members carried by said frame; a vertically extending bearing mounted on said guide members to slide vertically; a bearing mounted upon the upper end of said guide members at right angles thereto and being capable of adjustment vertically; means to adjust the vertical position of said last bearing; means to lock said bearing in its adjusted position; a disc revolvably mounted in said last bearing; means for rotating said disc; a relatively non-revolvble bevel gear carried by said disc rotatable therewith; a bracket revolvably mounted on said bevel gear; a vertically ex-

tending bearing carried by said bracket; a spindle revolvably mounted in said bearing; a pinion gear mounted on said spindle in mesh with said bevel gear; a sleeve revolvably mounted in said first vertical bearing; an operative connection between said sleeve and spindle; a piston engaging member detachably mounted in said sleeve.

7. A lapping machine comprising a frame; vertically extending guide members carried by said frame; a bracket mounted on said guide members adjustable vertically; means to adjust said bracket vertically; means to lock said bracket in its adjusted position; a disc revolvably mounted in the upper end of said bracket; a power device carried by said bracket adapted to rotate said disc; a bevel gear eccentrically but relatively non-revolvably mounted on said disc; means to vary the eccentric relation of said gear and disc; a bracket carried by said bevel gear; a connecting rod revolvably mounted at its upper end in said bracket; a pinion gear rigidly mounted on the upper end of said spindle in operative engagement with said bevel gear; a bearing slidably mounted in said guide members to slide vertically; a work engaging spindle revolvably mounted in said bearing to slide therewith; a flexible connection between the adjacent ends of said spindle and connecting rod; and means at the free end of said spindle for detachably securing a piston thereto.

8. A lapping machine comprising a frame; a bracket mounted in said frame adjustable longitudinally thereof; a disc revolvably mounted in said bracket; a bevel gear adjustably mounted on said disc to rotate therewith but relatively non-revolvble and adjustable radially; a bearing slidably mounted in said frame; a work engaging spindle revolvably mounted in said bearing to slide therewith; a connecting rod connected at one end to said work holding spindle and having at its other end a pinion gear in operative engagement with said bevel gear; and means to rotate said disc.

In witness that we claim the foregoing we have hereunto set our hands this 31st day of March, 1922.
